UNITED STATES PATENT OFFICE.

ROBERT KAERSCHKE, OF DETROIT, MICHIGAN, ASSIGNOR TO ADAM BRANDAU, OF DETROIT, MICHIGAN.

GAME.

1,028,467.

Specification of Letters Patent.

Patented June 4, 1912.

Application filed December 7, 1911. Serial No. 664,471.

To all whom it may concern:

Be it known that I, ROBERT KAERSCHKE, a subject of the Emperor of Germany, residing at Detroit, county of Wayne, State of Michigan, have invented a certain new and useful Improvement in Games, and declare the following to be a full, clear, and exact description of the same, such as will enable others skilled in the art to which it pertains to make and use the same, reference being had to the accompanying drawings, which form a part of this specification.

My invention relates to an improvement in games, shown in the accompanying drawings and more particularly described in the following specification and claims.

The object of my invention is to provide a game board having a dished or inclined top with a plurality of numbered pockets adjacent to the edge adapted to receive a series of balls which may be driven into said pockets through the rotation of a top manually spun by the several contesting players.

In the drawings accompanying this specification:—Figure 1 is a plan view of the game board and top. Fig. 2 is a vertical cross-sectional view of the same.

Referring now to the letters of reference placed upon the drawings:—A denotes the top of a game board which may be constructed of wood, papier-mâché, or any other suitable material.

B indicates an upstanding rim encircling the board. C a plurality of numbered pockets arranged in circular form adjacent to said rim.

D is a spinning top, and D' is its pivotal post, rectangular in cross-section, from which the disk D² projects.

D³ is a stem rising from the disk which upon turning between the thumb and forefinger, serves to rotate the device.

E indicates a plurality of marbles or balls designed to enter the pockets C of the game board.

Having indicated the several parts by reference letters, the manner of playing the game will now be explained.

The several marbles or balls are placed on the board which naturally gravitates toward the center of the board owing to the dished or inclined formation of the latter. The spinning top D is now rotated near the center of the board by the thumb and forefinger

of one of the players as before explained, 55 whereupon the marbles gravitating toward the center of the board will come in contact with the squared faces of the post which serve to deflect them into, and in the direction of the surrounding pockets. If they 60 do not all enter the pockets immediately they continually gravitate toward the top and upon coming in contact therewith, will be deflected again and again until the top ceases to spin or the balls are housed within 65 the pockets. The number of the pocket indicates the points gained by the player; the player making the highest number of counts winning the game.

The marbles may be given different colors respectively corresponding with the colors of the pockets, or of a plurality of radiating stripes A' leading to the several pockets. When a marble of corresponding color enters a pocket of like color, it counts as 70 many points for the player as the pocket indicates. Should a marble enter a pocket not corresponding in color, the number of points indicated on the pocket may be deducted 75 from the player's score.

One of the marbles may be given a color not represented on the board and when this marble enters a pocket the count or number indicated on the pocket, may be doubled and added to the player's score. It would 80 therefore be one of the objects of the game to drive this marble into the pocket representing the highest number of points. In the event of one or more of the balls being 85 left out of the pockets when the top ceases 90 to spin, a certain arbitrary count may be deducted from the player's score for any unhoused ball.

Many other modifications of the manner of playing the game may be adopted without departing from the spirit of the invention.

Having thus described my invention, what I claim is:—

1. A game board having an inclined top 100 provided with a plurality of pockets near its outer edge, said pockets being arbitrarily colored, a plurality of balls colored to correspond with the colors of the pockets, and a top adapted when spun to deflect the balls 105 into said pockets.

2. A game board having a dished top provided with a plurality of pockets, a rim sur-

rounding said board, said top divided by contrasting color segments into a plurality of stripes leading to the pockets, a series of balls respectively colored to correspond with 5 said segments, and a top adapted when spun to deflect said balls into the pockets.

In testimony whereof, I sign this specification in the presence of two witnesses.

ROBERT KAERSCHKE.

Witnesses:

GRACE E. WYNKOOP,
SAMUEL E. THOMAS.
